UNITED STATES PATENT OFFICE.

FÉLIX BLOIS, OF PARIS, FRANCE.

APPARATUS FOR THE ENLARGING OF RINGS.

Application filed July 21, 1925, Serial No. 44,972, and in France August 14, 1924.

My invention relates to a hand operated jeweler's tool for enlarging finger rings.

The object of my invention is to produce a tool of simplified construction and the operations of which are rendered more rapid and convenient, thus increasing the output of the tool.

On the appended drawings showing by way of example an embodiment of my invention:

Fig. 1 is a central longitudinal section through the new tool, and

Fig. 2 a plan view thereof.

The essential parts of the tool are the base 1, the lever 2, the handle 3 and a pair of rollers 4 and 5. In the base 1 is mounted the axle 6 which is secured in position by means of its screwthreaded portion 8 and the nut 9.

Upon the said axle are keyed the smooth roller 4 and the pinion 10. The lever 2 is rotatable on the axle 6, it being held in place by the collar 11 of the latter. In said lever is mounted the forked holder 12 which is slidable, without rotation, in a square recess and the cylindrical recess 14 of the said lever. On the latter is also mounted the handle 3 which is screwed therein with easy friction.

Within the said handle is fitted the cylindrical portion 15 of the fork 12, and the handle can rotate about portion 15 but is secured thereto as regards lengthwise motion, by means of the shanks 16 and 16^a and the set screw 17.

The square portion 13 of fork 12 receives the removable roller 5 as well as the pinion 18 secured thereto, and also the spindle 19 which serves as a shaft for their rotation. The roller 5, which is suitably grooved, is therefore interchangeable.

The operation is as follows:

The annular portion of the ring inserted between the separated rollers 4 and 5, so as to fit upon the smooth roller 4, the smooth inner portion of the ring thus being in contact with roller 4.

Now the handle 3 is screwed into the lever 2, thus advancing the fork 12 and its roller 5 toward roller 4 until the necessary pressure upon the ring is obtained and thereupon the lever 2 and the handle 3 are rotated about the axle 6.

Due to this rotation, the roller 5 is caused

to rotate on its axis through the medium of the meshing pinions 10 and 18 after the manner of a planetary pinion, since the stationary pinion 10 will rotate the pinion 18 in mesh therewith. The roller 5 will thus roll upon the ring, and due to the pressure upon the handle 3, will exert a rolling or laminating action upon the metal of the ring, and in variable degree depending upon the desired enlargement of the ring.

In order to determine the amount of enlargement which depends upon the extent to which handle 3 is screwed inwards, I provide upon said handle a smooth graduated portion 20 (Fig. 2) adapted to enter the socket in lever 2; upon the edge of the latter is provided an indicating line 21 co-operating with said graduations.

While base 1 may be mounted upon a wall, I prefer to secure it upon a table, in which position, the operations upon the ring may be closely observed. The disposition of the rollers permits the rings to be rapidly inserted and removed without the necessity of dismounting any part of the apparatus. The grooved roller is removable and therefore, a roller suitable to the shape of the ring may be used. It should also be noted that the tool can be operated by one hand and by means of a single part, i. e. the handle.

Obviously the tool is susceptible of various modifications, and the several elements thereof may be replaced by others serving a like purpose or producing the same effect.

I claim:

In an apparatus for enlarging rings, a base, an axle, a ring supporting roller fixed on said axle, a handle rotatably secured on said axle, a roller support longitudinally movable in said handle, a spindle in said roller support, a grooved roller rotatably mounted on said spindle, intermeshing pinions associated with said ring supporting roller and said grooved roller to cause rotation of said grooved roller on movement of said handle about said axis, and means comprising rotation of the handle about its axis to move said support for adjustably positioning said grooved roller in relation to said ring supporting roller.

In testimony whereof he has affixed his signature.

FÉLIX BLOIS.
